CLAIM

The ornamental design for an information handling system as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 depicts an enlarged view of portion "9" as shown in FIG. 1;

FIG. 10 depicts an enlarged view of portion "10" shown in FIG. 2;

FIG. 11 depicts an enlarged view of portion "11" shown in FIG. 8; and,

FIG. 12 depicts another front perspective view of the information handling system of FIGS. 1-11, shown with environment.

The even-dash broken line boxes represent the extents of the enlarged views and form no part of the claimed design. The additional set of even-dash broken lines, showing the rest of the information handling system in FIG. 8, represent environment that forms no part of the claimed design. All other even-dash broken lines in the drawings illustrate portions of the information handling system and form no part of the claimed design. The dash-dot broken lines represent the boundaries of the claim and form no part thereof.
